UNITED STATES PATENT OFFICE

ISIDORE SIMON, OF CHICAGO, ILLINOIS

LAST

Original application filed October 12, 1927, Serial No. 225,763. Divided and this application filed December 9, 1929. Serial No. 412,745.

This invention pertains to the general class of devices on which shoes, and the like, for correcting foot ailments may be formed, and embodies scientific principles as applied to 5 shoes and their innersoles as disclosed in the application.

The present application is a division of my copending application filed October 12, 1927—Serial No. 225,763.

10 A further object of this invention is to provide a last on which shoes, or the like, having a particular construction may be formed, and which are intended to prevent and correct abnormal distribution and abnormal 15 direction of forces in various parts of the human foot.

A further object of this invention is to provide a last for the production of devices, particularly shoes and their innersoles, for 20 preventing, correcting and checking undue strains and stresses and abnormal distribution of forces in and between the parts of the human foot, and for treating feet subjected to said abnormal stresses, strains and 25 forces.

A further object of this invention is the production of apparatus for producing devices, such as shoes and their innersoles, for the purpose of preventing, correcting and 30 checking abnormal strains and stresses and abnormal distribution of forces in the human foot, and for treating feet subjected to abnormal forces.

Many other objects and advantages of the 35 construction herein shown and described will be obvious to those skilled in the art from the disclosure herein given.

To this end, my invention consists in the 40 novel construction, arrangement and combination of parts herein shown and described, and more particularly pointed out in the claims.

In the drawing, wherein like reference 45 characters indicate like or corresponding parts:

Fig. 1 is a top plan view of a last embodying features of the present invention;

Fig. 2 is a longitudinal sectional elevation 50 of a last showing an innersole applied there-

to, the view being taken as indicated by the line 2—2 of Fig. 1;

Fig. 3 is a transverse sectional elevation of the last shown in Figs. 1 and 2 with an innersole applied thereto, and taken substantially 55 as indicated by the line 3—3 of Fig. 1;

Fig. 4 is a transverse sectional elevation of the last taken on the line 4—4 of Fig. 1 showing an innersole applied thereto, and illustrating the position of a wedge, a concavity 60 and a split innersole;

Fig. 5 is a top plan view of a modified form of last showing an elevation opposite the lateral tubercle of the oscalcis; and

Fig. 6 is a transverse sectional elevation of 65 an innersole showing a concavity for the lateral as well as the median tubercle, and adapted for use in conjunction with the modified form of last shown in Fig. 5.

The present invention comprises a last 35 70 having a depression formed therein as at 36 (Fig. 1) to receive an embossed portion 26 previously formed on an innerside 25, the greatest elevation of the embossed portion and the greatest depth of the depression 36 75 being located at a point on the center line of the foot opposite the shafts of the second and third metatarsal bones, respectively, at the junction of their medial and distal thirds. At this point is formed one angle of an isosceles triangle, the base and head of the fifth metatarsal being at the other two points, the base of the triangle extending from the point of juncture mentioned above to the head of the fifth metatarsal. This formation of the 80 depression 36 is accomplished by tooling out the last to accommodate the embossed portion 26 of the innersole. 85

The last is further formed with an elevation or boss 39 located approximately centrally 90 of the heel portion. The elevation or boss-like formation fits into the cavity of a depression 29 previously formed in the heel seat of the innersole.

The heel of the last is further shaped to receive the elevation on the innersole caused by a wedge 27, by cutting down the material of the last shown at 41, forming two inclined planes 41 and 42, the plane 41 having its lower point located at the medial or inner bor- 100

der and its highest point terminating at the center line (see Fig. 1), while the longitudinal inclined plane 42 has its lowest point located at the posterior border 43 of the heel and terminates at the junction of the heel 44 and shank 45, with the exception of the additional elevation 39 at a point located beneath the median tubercle of the oscalcis and adapted to fit into the concavity or depression 29 on the heel seat of the innersole as above described.

In the modified form shown in Fig. 5, the last is provided with an elevation or boss 47 adapted to engage a depression 46 (Fig. 6) previously formed in the innersole for the lateral tubercle of the oscalcis.

It will be observed from the foregoing description that the present invention provides a last having a depression formed therein for receiving an embossed portion previously formed on an innersole and having its greatest elevation located at a point on the center line of the foot opposite the shafts of the second and third metatarsal bones at the junction of their medial and distal thirds; that the present invention provides a last having an elevation or boss-like formation adapted to fit into a concavity or depression previously formed in the heel seat of an innersole at a point located beneath the median tubercle of the oscalcis; and that the present invention contemplates a last having two inclined planes, one of which has its lower point located at the medial or inner border and its highest point terminating at the center line of the last while the other longitudinal inclined plane has its lowest point located at the posterior border of the heel and terminates approximately at the junction of the heel and shank portion of the last except for the elevation or boss located beneath the median tubercle of the oscalcis.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a shoe last in combination, a depression in the shank thereof opposite the metatarsal bones, and the inner rear edge of the heel portion laterally of the median tubercle of the oscalcis being lowered a substantial predetermined amount with respect to the remaining portion of the heel.

2. In a shoe last in combination, a depression in the shank thereof opposite the metatarsal bones, an embossed elevation in the heel portion thereof opposite the median

tubercle of the oscalcis, and the inner rear edge of the heel portion laterally and to the rear of the median tubercle of the oscalcis being lowered a predetermined amount with respect to the remainder of the heel portion.

3. In a shoe last of the kind described and in combination, a depression in the shank thereof, an elevation in the heel portion thereof opposite the median tubercle of the oscalcis, a second elevation in the heel portion thereof opposite the lateral tubercle of the oscalcis, and the inner portion of the heel thereof receding toward the inner rear edge of the heel.

4. A shoe last having a depression in the shank thereof, the greatest depth of said depression being approximately along a vertical line intersecting the center line of the foot and also intersecting a line joining the second and third metatarsal bones, the latter line drawn from the junction of the medial and distal thirds of each of said metatarsal bones of the foot for which the last is constructed, a convex elevation in the heel thereof, said elevation terminating a substantial distance inside the marginal edges of the heel portion, and a receding inner heel portion.

In witness whereof, I hereunto subscribe my name this 5th day of December A. D., 1929.

ISIDORE SIMON.
